TABLE-CLOCK

Georges Ducommun, Grenchen, Switzerland, assignor to Baumgartner Freres S.A., Grenchen, Switzerland

Filed Aug. 22, 1961, Ser. No. 66,462

Claims priority, application Switzerland Mar. 1, 1961

Term of patent 14 years

(Cl. D42—7)

FIG. 1

The element beneath the clock housing is a circular set screw which is centered thereon. The round member is centered on a triangular base.

I claim:

The ornamental design for a table-clock, substantially as shown and described.
